UNITED STATES PATENT OFFICE.

FRANK L. HARMON, OF BEVERLY, MASSACHUSETTS, ASSIGNOR TO THE SINGER MANUFACTURING COMPANY, OF ELIZABETH, NEW JERSEY, A CORPORATION OF NEW JERSEY.

DUPLEX FASTENER-SETTING MACHINE.

1,426,473.

Specification of Letters Patent. Patented Aug. 22, 1922.

Application filed June 9, 1920. Serial No. 387,549.

To all whom it may concern:

Be it known that I, FRANK L. HARMON, a citizen of the United States, residing at Beverly, in the county of Essex and State 5 of Massachusetts, have invented certain new and useful Improvements in Duplex Fastener-Setting Machines, of which the following is a specification, reference being had therein to the accompanying drawings.

10 This invention relates to a punching, or punching and fastener setting machine of that type where two pieces of material may be worked upon simultaneously. It provides novel arrangements of the punching 15 and setting elements together with means for ejecting the punchings, so that they may not interfere with the proper operation of the elements, nor be ejected in a manner to cause annoyance to the operator.

20 For a more complete understanding of this invention, one embodiment thereof has been shown in the accompanying drawings in connection with a machine of the type disclosed in the patent to Harmon 1,262,336, 25 April 9, 1918, though it should be recognized that it is not limited to this type of machine, but might be embodied if desired in machines of other types.

In these drawings,

30 Fig. 1, is a fragmentary elevation showing the punching and setting mechanisms in retracted position.

Fig. 2, is a fragmentary elevation with parts in section showing the parts in position with the materials punched and the fasteners about to be set.

Fig. 3, is a detail showing the fasteners set and the punchings ejected.

Fig. 4, is a plan partly broken away of the 40 double ended punch and set element, and,

Fig. 5, is a detail showing a modification.

Referring to Fig. 1, A represents a yoke frame having spaced sleeves 1 and 2 carrying telescopically arranged therein the set 45 elements 3 and 4 and the punch elements 5 and 6. Punch elements 5 and 6 are solid throughout instead of hollow as in the patent above mentioned, and serve as anvil members to press material against cutting 50 punch elements 7 and 8 carried by central block 9 which is supported by a bracket 10 from the yoke frame A.

At 11 and 12, are shown actuating levers operating in the manner disclosed in the 55 above mentioned patent, to actuate in suit-

able sequence the telescopically arranged punch and set elements.

Surrounding the cutting edges 7 and 8 of the block 9, are die portions 13 and 14 which operate in conjunction with the set elements 60 3 and 4 to set the fasteners. Block 9 is recessed as shown at 15 between the opposed cutting and setting end portions and within this recess is made fast a double armed leaf spring 16. The free ends of spring 16 impinge against the heads of ejector pins 17 and 18 within the recess 15, these pins being 65 slideable in perforations in the block 9 and with their outer ends extending into recesses 19 and 19' formed within and 70 bounded by the cutting edges 7 and 8, these recesses forming sockets for the reception of the punchings removed by the cutting edges.

As shown in Figs. 2, 3, and 4, spring 16 75 is retained in position by means of a pin 20 passing therethrough and made fast in block 9, and in Fig. 5, a modification is shown in which the spring is held between the jaws 21 and 22 of a pin 23 which passes 80 laterally through the block 9, these jaws 21 and 22 being bent laterally externally of the block 9 to retain the pin 23 in position. By this form of fastening, no perforation of the spring is required.

In operation a piece of material is passed between each end of the block 9 and the mating telescopic punching and set elements.

On actuation of the levers 11 and 12, the 90 elements 5 and 6 are made to press the material against the oppositely disposed cutting edges, and during the movement to that position are caused by suitable means, such as are shown in the above mentioned patent, to take the eyelets therewith into positions 95 as shown in Fig. 2. The set elements 3 and 4 are then caused to approach the block 9 thus forcing the eyelets through the material and clinching the same between the mating clinch surfaces.

During the punching of the material, the plungers or pins 17 and 18 are caused to 100 retract by the pressure of the punchings thereagainst, in opposition to the spring 16, these parts being held in this position during the setting of the eyelets. The sets 3 and 4 are then caused to retract, followed closely thereafter by the solid end punch elements 5 and 6, whereupon the pressure holding the punchings within the socket 19 110

and 19' is relieved so that the pins 17 and 18 are free to eject them by the action of the spring 16. The frame A is then caused to move relative to the work, to position the 5 elements for the succeeding punching and setting operations.

Having thus described one embodiment of this invention, what is claimed is

1. In combination, a frame, punch-elements sustained thereby and directed each toward the other, a double-ended cutting punch sustained by said frame intermediate said punch-elements and adapted for cooperation therewith, and punching-ejector 45 means carried by said punch.

2. In combination, a frame, a double-ended cutting punch sustained thereby, co-operating punch-elements sustained by said frame in permanent register with and at 50 opposite ends of said punch, and punching-ejector means carried by said punch.

3. In combination, a frame, a double-ended cutting punch sustained thereby, co-operating cutting elements sustained by 55 said frame at opposite ends of said punch, and punching-ejector elements acting in opposition to said punch elements.

4. In combination, a block having on opposite faces punch elements and sockets 60 for the punchings, cooperating punch elements acting in conjunction respectively with the first-named punch elements, a punching-ejector for each of said sockets, and means to actuate said ejectors and acting 65 in opposition to the second-named punch elements.

5. In combination, a block having punch 70 elements and sockets for the punchings on opposite faces, means for pressing work against said elements to punch the same and force the punching into said sockets,

and means for ejecting the punchings from said sockets on the retraction of said work pressing means.

6. In combination, a block having opposed punch elements and fastener setting surfaces, means for pressing work against 45 said punch elements to punch the same, setting means telescopically related to said pressing means and co-operating with said 50 setting surfaces to set fasteners in the holes punched, and oppositely acting ejector means for freeing the punchings from said punch elements on the retraction of said pressing means.

7. A double ended cutting punch, opposed punching ejector elements carried thereby, and a spring interposed between 55 said elements to urge them in directions to eject punchings.

8. A double ended cutting punch, opposed punching ejector elements carried thereby, and a double armed leaf spring interposed between said elements to urge them 60 in directions to eject punchings.

9. A double ended cutting punch, a recess in said punch between said ends, pins 65 for ejecting punchings from said ends and projecting within said recess, and a double armed spring carried in said recess for urging said pins outwardly to eject punchings.

10. A double ended cutting punch, a recess in said punch between said ends, pins for ejecting punchings from said ends and projecting within said recess, a double 70 armed spring carried in said recess for urging said pins outwardly to eject punchings, and means for retaining said spring in said recess.

In testimony whereof, I have signed my 75 name to this specification.

FRANK L. HARMON.
